United States Patent Office

Des. 183,941
Patented Nov. 18, 1958

183,941

MAIL BOX

Charles A. Masso, Erie, Pa.

Application November 7, 1957, Serial No. 48,364

Term of patent 14 years

(Cl. D74—9)

FIG. 2

FIG. 1

FIG. 3

Fig. 1 is an isometric view of a mail box showing my new design;

Fig. 2 is another isometric view thereof as it appears in closed position; and

Fig. 3 is a side elevational view thereof, the side opposite thereto being similar in appearance.

The back of the mail box is plain and unornamented.

I claim:

The ornamental design for a mail box, as shown and described.
